UNITED STATES PATENT OFFICE.

EMIL FREDERICK BOWMAN, OF MARSHALLTOWN, IOWA.

DRINKING-FOUNTAIN.

1,337,637.

Specification of Letters Patent. Patented Apr. 20, 1920.

Application filed June 23, 1919. Serial No. 306,031.

To all whom it may concern:

Be it known that I, EMIL F. BOWMAN, a citizen of the United States, residing at Marshalltown, in the county of Marshall 5 and State of Iowa, have invented certain new and useful Improvements in Drinking-Fountains, of which the following is a specification.

This invention relates to improvements in 10 drinking fountains particularly adapted, though not necessarily limited in its use for poultry, and one of the objects of the invention is to provide an improved simple, compact and efficient apparatus of this 15 character embodying a tank having a discharge outlet for the water and provided with a valve for controlling such outlet, the opening and closing movements of the valve being respectively controlled by the 20 closing and opening operation of the tank.

To the attainment of these ends and the accomplishment of other new and useful objects as will appear, the invention consists 25 in the features of novelty, in substantially the construction, combination and arrangement of the several parts hereinafter more fully described and claimed and as shown 30 in the accompanying drawing illustrating the invention and in which;

Figure 1 is a vertical sectional view of the invention showing the parts in one position in full lines and in another position in dotted lines.

Fig. 2 is a horizontal sectional view as 35 taken on line 2—2, Fig. 1.

In the drawing the numeral 10 designates 40 an open tank of any desired size and configuration and constructed of any suitable material and is provided with an open trough 11, on the outside thereof, preferably arranged to extend therearound and may be of any desired depth. The tank 45 is provided with a discharge outlet 12 adjacent its bottom for delivering the liquid from the tank into the trough. Within 50 the tank and extending along the bottom thereof inwardly from the outlet 12 is a conduit or passage 13 which is closed to the inside of the tank except through a suitable inlet opening 14 and through which 55 inlet the liquid flows into the passage 13 to be delivered into the trough 11.

A valve designated generally by the 60 numeral 15 is arranged within the tank 5 and is pivotally mounted intermediate its 65 ends as at 16 in any suitable manner such as

between two ears or bearings 17. The end 18 of the valve is arranged over the inlet opening 14 and is preferably weighted so as to tend normally to close the opening 14 and 60 when the valve is in a closing position the end 19 of the valve will be elevated.

An air pipe 20 is also arranged within the tank and has communication at its outlet end 21 with the conduit or passage 13 65 within the tank. The inlet end 22 of the pipe extends to a point adjacent the top of the tank and above the water level therein.

The tank is provided with a cup shaped closure having a top 23 provided with a 70 handle 24 and a body 25 which telescopes with the tank 10. The body portion 25 is of such a length that when the closure is in position, the lower end of the body will engage the end 19 of the valve and shift the 75 valve to open the inlet 14 of the conduit passage 13 to permit the contents of the tank to be delivered through the outlet 21 into the trough 11. When the closure is removed, the weighted end of the valve will 80 cause the valve to drop and close the inlet 14.

In use the closure is removed which will 85 permit the one end 18 of the valve to close the opening 14. The tank may then be filled and when filled the inlet end 22 of the air discharge pipe 20 will be above the liquid level. The closure is then placed in position so that its body 25 will telescope with the tank and when the lower end of the body 90 engages the portion 19 of the valve, the valve will be shifted to open the inlet 18. The valve will remain in this open position as long as the closure is in position. A flanged shoulder 26 may be provided on the closure to rest upon the top edge of 95 the wall of the tank. As the closure is placed in position, the air which has been confined at the top thereof above the liquid will escape through the pipe 20.

The conduit or passage 13 may be of any 100 size and shape but is preferably flat on the top and wider at the end having the inlet 14 than at the outlet end so as to permit of a generous size inlet 14 and a support for the valve.

While the preferred form has been herein 105 shown and described, it is to be understood that various changes may be made in the details of construction and in the combination and arrangement of the several parts without departing from the spirit of this invention.

What is claimed as new is:—

1. A drinking fountain embodying an open tank having a discharge outlet adjacent its bottom, a valve disposed entirely within the tank for controlling the outlet, a closure for the tank, and means connected with the closure and extending into the tank to actuate the valve to open the outlet when the closure is in position. 5
- 10 2. A drinking fountain embodying an open tank having a discharge outlet adjacent its bottom, a valve disposed entirely within the tank for controlling the outlet, a closure for the tank, means connected with the closure and extending into the tank to actuate the valve to open the outlet when the closure is in position, and an air outlet also within the tank leading from the upper portion of the tank and having 15 communication with the said outlet. 20
- 25 3. A drinking fountain embodying an open tank having a discharge outlet adjacent its bottom, a trough outside of the tank for receiving the water therefrom, a valve within the tank for controlling the outlet, said valve operating to normally close the outlet, and a cover element telescoping with the tank, a portion of the cover element contacting with the valve to shift 30 the latter and hold the same open when the cover element is in position. 35
- 40 4. A drinking fountain embodying an open tank having a discharge outlet adjacent its bottom, a trough outside of the tank for receiving the water therefrom, a valve within the tank for controlling the outlet, said valve operating to normally close the outlet, a cover element telescoping with the tank, a portion of the cover element contacting with the valve to shift the latter and hold the same open when the cover element is in position, and an air outlet pipe within the tank and leading from a point adjacent the top of the tank and having 45 communication with the said outlet. 50
5. A drinking fountain embodying a tank having an outlet opening adjacent its bottom, a pivotally mounted valve within the tank for controlling the outlet, a closure element telescoping with the tank, the end
- of said element adapted to engage the valve on one side of the pivot to shift the valve to open the outlet as the closure is placed in position, said valve operating automatically to close the outlet when the closure is removed, and an air pipe within the tank and leading from a point above the water level and communicating with the said outlet. 55
6. A drinking fountain embodying an open tank having a discharge outlet adjacent its bottom, a closed conduit extending from the outlet and into the tank at the bottom thereof, said conduit having an inlet opening within the tank, a pivoted valve within the tank tending normally to close the said inlet, a portion of the valve extending to the other side of the pivot, a closure for the tank, said closure telescoping with the tank and adapted to engage the said portions of the valve on the other side of the pivot to shift the valve and open the said inlet as the closure is telescoped with the tank, and means for permitting the escape of the air from the tank and adjacent the bottom thereof. 70
7. A drinking fountain embodying an open tank having a discharge outlet adjacent its bottom, a closed conduit extending from the outlet and into the tank at the bottom thereof, said conduit having an inlet opening within the tank, a pivoted valve within the tank tending normally to close the said inlet, a portion of the valve extending to the other side of the pivot, a closure for the tank, said closure telescoping with the tank and adapted to engage the said portion of the valve on the other side of the pivot to shift the valve and open the said inlet as the closure is telescoped with the tank, and means for permitting the escape of the air from the tank and adjacent the bottom thereof, the said means embodying an air pipe entirely within the tank and leading from a point above the liquid level of the tank and having communication with the said discharge outlet. 75 80 85 90 95

In witness whereof, I hereunto subscribe my name to this specification.

EMIL FREDERICK BOWMAN.
